GEORGE K. WALKER, OF WEBSTER GROVES, MISSOURI.

GROCER'S DISPENSING BIN.

1,101,822.

Specification of Letters Patent. Patented June 30, 1913.

Application filed August 6, 1913. Serial No. 783,337.

To all whom it may concern:

Be it known that I, GEORGE K. WALKER, citizen of the United States, residing at Webster Groves, in the county of St. Louis and State of Missouri, have invented certain new and useful Improvements in Grocers' Dispensing-Bins, of which the following is a full, clear, and exact description, reference being had to the accompanying drawings, forming a part hereof.

My invention has relation to improvements in grocers' dispensing bins; and it consists in the novel details of construction more fully set forth in the specification and pointed out in the claims.

In the drawings, Figure 1 is an elevation of a frame or cabinet containing a battery of bins; Fig. 2 is a perspective of the bin on a larger scale, the bin being closed; Fig. 3 is a vertical middle longitudinal section thereof; and Fig. 4 is a vertical transverse sectional detail on the line 4-4 of Fig. 3.

The present improvement is directed to tilting bins for grocers, and merchants generally, and has for its object to provide a tilting bin the lid of which will remain in permanent engagement with the bin for both a closed and open position of the latter, the bin being so mounted as to bring its center of gravity to one side of its axis of oscillation, thereby assisting the bin to remain in either its closed or open position.

A further object is to provide the bin with a hinged lid which will close tightly over the bin when the latter is swung to its closed position, thereby excluding insects, dust and foreign matter, the invention possessing further and other advantages better apparent from a detailed description thereof which is as follows:

Referring to the drawings, F represents a frame or cabinet of any approved construction and within the purview of the skilled mechanic, the same having disposed therein in pairs, suitable posts or uprights 1, 1', as shown. Traversing the bottom portions of the front series of uprights 1 is a horizontally disposed hinge-rod 2 about which is free to oscillate between each pair of uprights, a tilting platform 3, the same being preferably provided with pairs of depending ears or lugs 4, 4', loosely embracing the rod, the edges of the platform being provided with upturned flanges 5, 5', to prevent the bin 6 removably deposited thereon from sliding off when the bin (and platform)

is tilted to open position. As arranged, the bin and platform tilt as a unit about the axis of the rod 2, said axis being eccentric to the center of gravity of the bin and its contents for both the closed and open (or tilted) position of the bin (Fig. 3). The front wall of the bin is provided with a handle 6 by which it may be readily manipulated.

Suspended by hinges or loops 7, 7, about a rear horizontal rod 8 traversing the upper portions of the series of posts 1' is a lid 9, the sides and rear wall of the lid overlapping the walls of the bin so as to make an effective joint therefor. The roof of the lid has a double slope forward, there being disposed on the inner face of the forward sloping portion at a point contiguous to, and forward of, the angle between the slopes, an angle bracket 10 which strikes the rear wall of the bin when the latter is tilted forward, thus arresting further movement of the bin in that direction. When the bin is tilted back under the lid, the rear wall of the bin strikes the rear wall of the lid below its axis of suspension, thereby forcing the front end of the lid against the bin so that a positive and effective closure is always insured.

Details illustrated but not alluded to are common in the art and require no description in the present connection.

The operation is obvious:—When the bin is tilted backward under the lid (Fig. 3) the latter will close effectively over the bin, the center of gravity of the bin being rearward of the axis of oscillation thereof, so that it positively remains in said closed position until disturbed or dislodged therefrom. As the bin is tilted forward or outward, the lid will rise slightly (see dotted position of parts Figs. 3) but will again settle to its normal position by the time the bin is arrested by the lug or bracket 10 (Fig. 3). With the bin thus tilted to open position, it is apparent that its center of gravity will shift, being now forward of the axis of oscillation of the bin, so that the bin remains in such open or tilted position until forced back under the lid. The sloping roof of the lid allows for the outward or forward tilting of the bin without binding, it being clear from Fig. 3, that the outer face of the front wall of the bin is practically out of contact with the roof of the lid, the latter resting merely on the upper edge of said front wall. As stated before, the closing of

the bin drives the lid firmly against it, thus insuring a dirt-proof and insect-proof joint between the parts. The free edge of the lid is preferably reinforced by a bead *b* as understood in the art. By lifting the lid when the bin is tilted outwardly, the latter can be readily removed from its platform should this be desired.

It will be seen (Fig. 3) that when the bin is tilted outwardly approximately one-half of its opening is exposed, which is ample for purposes of inserting the hand (and scoop if any be used) to get at the contents of the bin.

The term "bin" is intended of course, to cover any container or receptacle whatsoever, and should be understood in its broadest sense.

Having described my invention, what I claim is:—

1. In combination with a lid hinged to swing about a fixed axis, a bin rotatable about a fixed axis and having its open end engaging the lid, and operating to lift the lid with an oscillation of the bin away from the axis of the lid, and means on the bin for engaging the rear of the lid at a point below the axis of the lid to force the free edge of the lid into positive engagement with the bin with the oscillation of the latter to its normal position under the lid.

2. In combination with a lid hinged to swing about a fixed horizontal axis disposed at one end of the lid, said lid having side walls and a roof sloping downwardly and outwardly from said axis, a bin having an open top and oscillating along a bottom horizontal axis positioned eccentrically to the center of gravity of the bin, the top of the bin being permanently engaged by the lid and operating to tilt outwardly from under the lid to expose a section of the

opening of the lid, whereby the axis of oscillation of the lid remains eccentric to the center of gravity thereof, such center shifting 45 to a point on the side of the axis opposite to that occupied for a closed position of the bin, and means on the lid for arresting the outward tilting movement of the bin.

3. In combination with a bin open at the top, a hinge rod disposed along the bottom of the bin to one side of the center of gravity thereof, a rod disposed rearward and above and parallel to the first rod, a lid having its rear end hinged to the last mentioned rod 55 and having side walls and a roof engaging the top of the bin, the roof of said lid sloping downwardly and outwardly from the hinge axis of the lid, the bin being tiltable outward from under the lid to expose a 60 section of its open end, and means carried by the roof of the lid adapted to engage the rear wall of the bin and thereby arrest the same in its outward tilting movement, the center of gravity of the bin shifting from 65 one side of the axis of oscillation thereof to the opposite side with a tilting of the bin from closed to open position.

4. In combination with a lid having side and rear walls and a sloping top or roof, 70 and hinged about the rear wall, a bin oscillating about an axis eccentric to the center of gravity thereof and in permanent contact with the lid, the rear wall of the bin being adapted to impinge against the inner 75 face of the rear wall of the lid and thereby force the front of the lid into positive engagement with the bin.

In testimony whereof I affix my signature, in presence of two witnesses.

GEORGE K. WALKER.
